ANTENNA

Robert W. Masters, Erlton, N. J., assignor to
 Radio Corporation of America, a corporation
 of Delaware

Application January 27, 1945, Serial No. 574,899

30 Claims. (Cl. 250—33)

1

This invention relates to radio antennas, and more particularly to improvements in antennas of the type employing sheet radiators, such as are described in my copending U. S. Patent Application Ser. No. 574,898, filed on the same date as this application and entitled "Antenna."

The principal object of the present invention is to provide an improved antenna of the sheet radiator type in which the sheets are so shaped as to provide greater vertical directivity than is obtained with the rectangular sheet radiators described in the above-mentioned application, while retaining the advantages of broad-band characteristics and simplicity of structure.

The invention will be described with reference to the accompanying drawing, of which:

Figure 1 is an isometric view of a single layer turnstile type antenna structure embodying the present invention,

Figure 2 is an elevational view of a multiple-layer structure of the type shown in Figure 1,

Figure 3 is a schematic view of a radiator element similar to those in the structures of Figures 1 and 2, but of modified form,

Figure 4 is a perspective view of a radiator element of the type illustrated in Figure 3, wherein the sheet comprises a plurality of parallel conductive rods, and

Figure 5 is an elevation of a dipole structure according to the invention, wherein the sheet elements are comprised of wire networks.

Referring to Figure 1, four flat plates or sheets 1, 3, 5 and 7 are disposed radially at 90° intervals around a tubular conductive mast 9. One edge of each sheet lies parallel to and closely adjacent the mast 9. This edge is in each case connected at its top and bottom to the mast 9, at the points 11 and 13 respectively. Each sheet is approximately five-eighths wavelength long, at the mean frequency at which the system is to operate, and has a maximum width of substantially one-quarter wavelength.

The side of each sheet away from the mast 9 is provided with a broad V-shaped notch or cut-out portion extending in width along the entire length of the sheet, and having a depth at the center of the sheet of approximately one-eighth wavelength. In other words, the sheet varies in width from one-eighth wavelength at its center to one-quarter wavelength at its ends.

Four wires or lines 15, 17, 19 and 21 extend up within the mast 9 as shown, or they may lie outside the mast. The lines 15, 17, 19 and 21 are connected to the sheets 1, 3, 5 and 7 respectively at the midpoints 22, 23, 25 and 27 of their edges

2

adjacent the mast. The mast 9 is preferably grounded. The lines are insulated from the mast, and may be surrounded with individual grounded coaxial sheaths. In this case, the mast 9 need not be of conductive material, but may be made of wood, for example.

In the operation of the system of Figure 1, the sheets 1 and 5 are energized as the elements of dipole, i. e. while a current I flows up the line 15, an equal current flows down the line 19, and vice versa. Similarly, the sheets 3 and 7 are energized as the elements of another dipole, through the lines 17 and 21. The currents in the lines 17 and 21 are in quadrature phase with respect to those in the lines 15 and 19, to provide a rotating field which is substantially uniform in a horizontal plane about the antenna, as in the conventional turnstile. The lines 15, 17, 19 and 21 may be connected together and to a transmitter or receiver in any known way to provide the required current phase relationships. One suitable connection is described in U. S. Patent 2,086,976, issued July 13, 1937, to G. H. Brown.

The current distribution in the sheet elements of the antenna of Figure 1 is such as to provide a vertical directivity approximating two layers of a turnstile antenna of conventional design such as that shown in the above-mentioned patent. The directivity is substantially twice that of a similar structure employing rectangular sheets, as described in my copending application Ser. No. 573,898. This improvement results from the shape of the sheets, which enforces the current to flow so that current maxima appear near the upper and lower edges of each sheet. Since the two maxima are separated vertically by approximately one-half wavelength, radiation in the vertical direction from the upper half of the sheet is cancelled by vertical radiation from the lower half.

Although the exact manner in which the current flows is not known at present, it has been found experimentally that the structure of Figure 1 has a relatively broad resonance characteristic, permitting efficient operation over a wide frequency band. It is believed that the operation is somewhat as follows:

Each of the sheets, for example the sheet 1, cooperates with the opposite sheet 5 to act as a parallel conductor transmission line section one-half wavelength long, shorter at its ends 11 and 13 and fed at its center 22. This results in a standing wave, with maximum voltage at the point 22 and zero voltages at the points 11 and 13. Each horizontal element of the sheet 1 con-

stitutes a radiator connected to the parallel line, with current flowing in it in a direction radial to the mast 9. The fields produced by these elements add together to produce a resultant field approximating that which would be provided by a pair of radiators of conventional form, spaced apart vertically one-half wavelength. However, the overall impedance remains relatively constant with variation in frequency, probably because the voltage distribution along the parallel line varies, changing the relative currents in the various horizontal elements of the sheet.

The vertical directivity may be increased, as in the conventional turnstile antenna, by providing a series of layers of elements spaced vertically along the mast 9. Since each of the sheets of Figure 1 corresponds in function to two radiators, the layers should be spaced one wavelength apart vertically, as illustrated in Figure 2.

The upper and lower edges and the cut-out portion of the sheet radiators may be rounded, rather than rectilinear as shown in Figure 1. Referring to Figure 3, a single sheet radiator element 101 is shown, supported on a conductive body 109 by connections 111 and 113 at the upper and lower ends respectively of the sheet 101. A transmission line 115 is connected to the midpoint 122 of the edge of the sheet 101 adjacent the body 109. The width of the sheet 101 varies smoothly from a minimum of approximately one-eighth wavelength at its center portion to a maximum of one-quarter wavelength near its upper and lower ends, the shape of said sheet may be likened to that of the cross-section of an hourglass.

The sheet radiators of my invention may be made of assembled structures, such as, screens or sheets of parallel conductors consisting of wires or rods. The term "sheet" as used herein and in the appended claims is intended to include such structures. Referring to Figure 4, a sheet radiator 201 of the same general hourglass outline of that of Figure 3 is made up of a plurality of parallel rods 203, supported radially of a mast 209 on a conductive bar 205 lying parallel to and closely adjacent the mast 209 and connected thereto at its upper and lower ends 211 and 213. The operation of the structure is similar to that of the above-described embodiments of the invention. However, the wind resistance is considerably less, an important consideration for out door structures.

Figure 5 illustrates another embodiment of the invention, including two sheetlike structures 301 and 305 connected to lines 315 and 317 for use as a dipole. Each structure comprises a network of wires 303, supported between upper and lower cross arms 306 and 307 secured to a mast 309. Bars 311 extend close to and parallel to the mast 309 between the upper and lower cross arms, and are connected at their centers 322 and 325 to the lines 315 and 317. The antenna of Figure 5 is particularly suited for directive reception of high frequency signals such as are used for television, although it may be used advantageously for transmission, or as an element of a turnstile array. Although it has been stated throughout the above description that the sheet elements are fed at their midpoints, they may be energized at any other point along the edge adjacent the mast if a lower input impedance is desired. The maximum impedance appears at the midpoint.

The invention has been described as an improved antenna including radiators in the form

of flat sheets, with one edge of each sheet grounded at its ends and fed at or near the center, and its other edge formed so that the sheet varies in width from a minimum at its center to a maximum at its ends. This arrangement forces currents to flow in the sheets in such manner as to provide considerable vertical directivity and broad resonance characteristics.

I claim as my invention:

1. A radio antenna including a support and at least one radiator element comprising a flat conductive member of generally oblong outline, with one substantially rectilinear edge lengthwise thereof positioned adjacent and parallel to said support, and grounded at its ends, the width of said member midway of said edge being approximately one-fifth of the length of said edge, said member being of a maximum width near the ends of said edge of approximately two-fifths of the length of said edge, and transmission line means connected to said member at a point on said edge.

2. A radio antenna including a grounded support and at least one radiator element comprising a flat conductive member of generally oblong outline, with one substantially rectilinear edge substantially five-eighths wavelength long lengthwise thereof positioned adjacent and parallel to said support, and connected to said support at its ends, the width of said member midway of said edge being approximately one-fifth of the length of said edge, said member being of a maximum width near the ends of said edge of approximately two-fifths of the length of said edge, and transmission line means connected to said edge at the midpoint of said edge.

3. A radiator element for radio antennas comprising a flat sheet of conductive material in the form of a rectangle provided with a triangular cut-out portion, with the apex of said triangle lying substantially at the center of said rectangle and the base of said triangle substantially coincident with one of the lengthwise edges of said rectangle and means for coupling radio frequency transducer means to the other lengthwise edge of said rectangle.

4. A radiator element for radio antennas comprising a flat conductive member of generally oblong outline, having one substantially rectilinear edge extending lengthwise thereof, said member varying in width from a minimum of approximately one-eighth wavelength at its center to a maximum of approximately one-quarter wavelength near each of its ends and means for coupling radio frequency transducer means to said rectilinear edge at substantially its midpoint.

5. A radiator element for radio antennas comprising a flat conductive member of generally oblong outline, having one substantially rectilinear edge extending lengthwise thereof, said member varying in width from a minimum at its center to a maximum near each of its ends and means for coupling radio frequency transducer means to said rectilinear edge.

6. A radiator element for radio antennas comprising a flat grid of conductive rods, said grid having a generally oblong outline, with one substantially rectilinear lengthwise edge and one curved lengthwise edge, said second edge being of such shape that grid is of minimum width at its center and of maximum width near its ends and means for coupling radio frequency transducer means to said rectilinear edge.

7. A radiator element for radio antennas com-

75

prising a flat sheet of conductive material of generally oblong outline, having one substantially rectilinear lengthwise edge and one curved lengthwise edge, said second edge being of such shape that sheet is of minimum width at its center and of maximum width near its ends and means for coupling radio frequency transducer means to said rectilinear edge at substantially its midpoint.

8. A radio antenna including a supporting member and at least one radiator element comprising a flat sheet of conductive material of generally oblong outline substantially one-quarter wavelength wide at its ends and substantially five-eighths wavelength long, and substantially one-eighth wavelength wide midway of its ends, said sheet having one substantially rectilinear edge lengthwise thereof positioned parallel to said support and grounded at its ends, and means for feeding said radiator element at a point on said edge. 10

9. A radio antenna including a supporting member and at least one radiator element comprising a flat screen of conductive material of generally oblong outline substantially one-quarter wavelength wide at its ends and substantially five-eighths wavelength long, and substantially one-eighth wavelength wide midway of its ends, said screen having one substantially rectilinear edge lengthwise thereof positioned parallel to said support and grounded at its ends, and means for feeding said radiator element at approximately the midpoint of said edge. 20

10. A radio antenna including a supporting member and at least one radiator element comprising a flat grid of conductive rods, said grid being of generally oblong outline substantially one-quarter wavelength wide at its ends and substantially five-eighths wavelength long, and substantially one-eighth wavelength wide midway of its ends, said grid having one substantially rectilinear edge lengthwise thereof positioned parallel to said support and grounded at its ends, and means for feeding said radiator element at a point on said edge. 30

11. A radio antenna including a support and a number of radiating wing members, said wing members having a generally oblong outline with a substantially rectilinear edge positioned adjacent to and parallel to said support, said wings being grounded at each end of said edge and transmission line means connected to said wings at a point on said edge intermediate said ends, said wings being substantially wider near their ends than at the intermediate points. 40

12. A radio antenna including a number of radiating wing members radially arranged about a conductive supporting member, said wing members having a generally oblong outline with a substantially rectilinear edge positioned adjacent to and parallel to said support, said wing members being grounded at each end of said edge to said support and transmission line means connected to said wing at a point on said edge intermediate said ends, said wings being substantially wider near their ends than at intermediate points. 50

13. A radio antenna including a number of radiating wing members radially arranged about a conductive supporting member, said wing members having a generally oblong outline with a substantially rectilinear edge positioned adjacent to and parallel to said support, said wing members being grounded at each end of said edge to said support and transmission line means connected to said wings at a point on said edge intermediate said ends, said wings being substantially 60

wider near their ends than at intermediate points, said wing members being substantially one quarter wavelength wide at their ends and substantially five eighths of a wavelength long, the width of said wings being substantially one eighth wavelength midway of their ends. 70

14. A radiator element for radio antennas comprising a flat sheet of conductive material of generally oblong outline having one rectilinear lengthwise edge five-eighths of a wavelength long and one curved lengthwise edge, said second edge being of such shape that said sheet is one-eighth wavelength in width at its center and one quarter wavelength in width at its ends and means for coupling radio frequency transducer means to said rectilinear lengthwise edge. 80

15. A radio antenna including a supporting member and at least one radiator element including a flat sheet of conductive material of generally oblong outline one quarter wavelength wide at its ends and five-eighths of a wavelength long, said sheet being one-eighth wide midway of its ends, said sheet having one rectilinear edge lengthwise thereof positioned parallel to said supporting member and grounded at its ends and means for feeding said radiator element at a point on said rectilinear edge. 90

16. A radio antenna including a supporting member and at least one radiator element including a flat screen of conductive material of generally oblong outline one quarter wavelength wide at its ends and five-eighths of a wavelength long, said screen being one-eighth wavelength wide midway of its ends, said screen having one rectilinear edge lengthwise thereof positioned parallel to said support and grounded at its ends and means for feeding said radiator element at the midpoint of said edge. 100

17. A radio antenna including a number of radiating wing members radially arranged about a conductive supporting member, said wing members having a generally oblong outline with one rectilinear edge positioned adjacent to and parallel to said support, said wing members being grounded at each end of said edge to said support and a transmission line connected to said wing members at points on their rectilinear edges intermediate said ends, said wing members being wider near their ends than at intermediate points. 110

18. An antenna system comprising, as a radiating or receiving element a substantially plane member of conductive material and of a generally quadrangular shape, said member having one lengthwise substantially straight edge and being grounded for radio frequency potential at the ends of said edge, said length being substantially equal to five-eighths of a wavelength at the operating frequency, the width of said member midway of said edge being substantially equal to one-fifth of the length of said edge, the maximum width of said member being near the ends of said edge and being approximately two-fifths of the length of said edge, a support for said member, and transmission line means connected to said member at a point on said edge. 120

19. An antenna system comprising a plurality of radiating or receiving elements, each said element including a substantially plane conductive member of generally quadrangular shape a quarter wavelength wide by five-eighths wavelengths long at the operating frequency and having a constricted width at the center of said member of an eighth wavelength disposed in a radial plane about a common axis and being substan- 130

stantially coextensive axially with each of the other said members; each of said members having the substantially linear lengthwise edge adjacent to and substantially parallel to said axis and closely spaced from the other said adjacent lengthwise edges, each of said members being grounded for radio frequency potential at the ends of said adjacent lengthwise edges, radio frequency voltages at the operating frequency at those points on the said linear edges of any two members which points lie in the same plane normal to said axis being substantially equal in amplitude and having an angular time phase difference substantially equal to the angle between the axial planes in which said two members are disposed, a support for said elements, and a transducer connected to said members.

20. An antenna system comprising, as radiating or receiving elements, a pair of substantially plane members of conductive material each of a generally rectangular shape, each said sheet having one lengthwise substantially straight edge and being grounded for radio frequency potential at the ends of said edge, a maximum width substantially equal to a quarter wavelength and a minimum width substantially an eighth wavelength at the operating frequency, a length substantially equal to five-eighths of a wavelength at the operating frequency, said members being disposed with said lengthwise edges closely adjacent and parallel to each other and in a common plane, a support for said members, and a transducer connected to said members.

21. An antenna system including a pair of radiating members arranged in a plane, each of said radiating members comprising a relatively long conductor and a plurality of relatively short conductors arranged in said plane normal to said long conductors and having lengths varying from a minimum at the central part of said long conductor to a maximum near the ends of said long conductor, the ends of the long conductors of said radiating members being connected together, and means to couple a transmission line to the long conductors of said radiating members at points intermediate the ends thereof.

22. An antenna system including at least a pair of radiating members, said radiating members being constituted by a pair of parallel conductors arranged to define a plane, a pair of further parallel conductors bridged across the first said parallel conductors substantially at the center thereof, a plurality of secondary conductors equidistantly spaced in said plane normal to said further conductors and having lengths varying from a minimum at the central part of said further conductors to a maximum near the ends of said further conductors and tertiary conductors connecting the ends of said secondary conductors remote from said further conductors to completely close the structure of said radiating members, and means to couple a transmission line to said further conductors at a point intermediate the first said parallel conductors.

23. An antenna system including a pair of radiating members, said radiating members being constituted by two pairs of collinearly arranged conductors arranged in parallel relationship to define a plane, a pair of further conductors each of said further conductors being connected to conductors of each pair of collinearly arranged conductors at the adjacent ends thereof, a plurality of secondary conductors arranged in said plane normal to said further conductors and having lengths varying from a minimum at the

central part of said further conductors to a maximum near the ends of said further conductors and tertiary conductors connecting the ends of said secondary conductors remote from said further conductors to completely close the structure of said radiating members, and means to couple a transmission line to said further conductors at points intermediate the collinearly arranged conductors.

24. An antenna system including a conductive supporting member and a pair of radiating members, said radiating members being constituted by a pair of conductors arranged adjacent and parallel to said supporting member, said conductors being connected together at the ends thereof through the intermediary of said conductive supporting member and a plurality of further conductors arranged in a single plane and normal to the first said conductors, said further conductors having lengths varying from a minimum at the central part of the first said conductors to a maximum near the ends of the first said conductors, said further conductors of maximum length being substantially a half wavelength apart at the operating frequency, and tertiary conductors connecting the ends of said secondary conductors remote from said further conductors to completely close the structure of said radiating members, and means to couple a transmission line to the first said conductors at points intermediate the lengths thereof.

25. An antenna comprising a pair of wing-like elements lying in the same vertical plane, each wing having a vertical edge, the edges of each pair lying relatively close together, each wing having top and bottom bases and a recessed edge connecting the top and bottom bases at the outer extremities thereof, the over-all height of said symmetrical antenna elements being greater than one-half wavelength and less than one wavelength at a desired operating frequency, the maximum width of the antenna as measured in a horizontal direction being of the order of one-half wavelength at said desired operating frequency, and the minimum width of the antenna as measured across its central portion in a horizontal direction being of the order of one-quarter wavelength at said desired operating frequency, connections connecting together the top and bottom edges of said wing-like antenna elements, a plurality of symmetrically arranged conductors connecting the recessed edge of each antenna element to the vertical edge thereof and means for connecting points located substantially centrally of said vertical bases to a two conductor transmission line.

26. Apparatus as claimed in claim 25 characterized by the fact that a conductor is provided for connecting the mid-point of the recessed edge of each antenna element to the mid-point of the straight edge of each antenna element and being further characterized by the fact that there are a plurality of symmetrically arranged conductors connecting points on said recessed edge other than said central point to opposite points on the straight line edge of each antenna element.

27. An antenna comprising two pairs of symmetrical winglike elements, each wing having a vertical edge, the edges of each pair lying relatively close together, each wing having top and bottom bases and a recessed edge connecting the top and bottom bases, the overall height of said symmetrical antenna elements being greater than one-

half wavelength and less than one wavelength at a desired operating frequency, the maximum width of the antenna as measured in the direction of said bases being of the order of one-half wavelength at said desired operating frequency, and the maximum width of the antenna as measured across its central portion in the direction of said bases being of the order of one-quarter wavelength at said desired operating frequency, connections connecting together the top and bottom bases of said wing-like elements, a plurality of symmetrically arranged conductors connecting the recessed edge of each antenna element to the vertical edges thereof, and means for connecting points located substantially centrally of 15 said vertical edges to a two conductor transmission line.

28. Apparatus as claimed in claim 27 characterized by the fact that a conductor is provided for connecting the mid-point of the recessed edge of each antenna element to the mid-point of the straight edge of each antenna element and being further characterized by the fact that there are a plurality of symmetrically arranged conductors connecting points on said recessed edge other than said central point to opposite points on the straight edge of each antenna element, the elements of one pair lying in one plane and the elements of the other pair lying in a different plane perpendicular to the first mentioned plane.

29. An antenna operable over a broad frequency range and suitable for use in television service, comprising a pair of antenna elements lying adjacent each other in the same plane and being of substantially the same size and configuration, the over-all shape of both elements being generally that of the cross-section of an hour-glass, each of said elements having a substantially straight conductive edge, top and bottom conductive bases, and a recessed conductive edge opposite the straight edge, said conductive edges and bases being connected together, short low impedance connections connecting the remote ends of the straight edge of one of said elements

5 to the remote ends of the straight edge of the other of said elements, the maximum over-all width of the antenna being of the order of one-half wavelength at a desired frequency of operation, the minimum width of the waist of said antenna at the desired frequency of operation being of the order of one-quarter wavelength and the length of said antenna as measured along one of said substantially straight bases being less than one wavelength and greater than one-half wavelength at said desired frequency of operation, and a plurality of symmetrically arranged conductors connected to and between the substantially straight edge of each antenna element and the recessed edge thereof.

10 20 25 30 An antenna as claimed in claim 29 characterized by the fact that said symmetrically arranged conductors include a conductor connected from the center of the straight base of each element to the center of the corresponding recessed edge of each element and a plurality of additional conductors connected to the recessed edge and straight base of each antenna element and lying between the top and bottom edges of each of said antenna elements.
